UNITED STATES PATENT OFFICE

GEORGE FRANCIS HARTMAN, OF ROSEDALE, MARYLAND, ASSIGNOR TO CONTINENTAL CAN COMPANY, INC., OF NEW YORK, N. Y., A CORPORATION OF NEW YORK

MACHINE FOR COATING CAN ENDS

Application filed November 22, 1928. Serial No. 321,148.

The invention relates to new and useful improvements in machines for coating can ends, and more particularly to a machine wherein the sealing material coated on the can end is discharged under pressure through a nozzle against the surface to be coated.

An object of the invention is to provide a machine of the above type with a device adjacent the nozzle having a chamber in which air may be trapped and compressed by the sealing material supplied to the nozzle so that when the valve is opened to permit the flow of the sealing material from the nozzle an auxiliary supply is provided under pressure which causes the sealing material to quickly fill the opening in the nozzle and to be discharged therefrom in a stream of full capacity.

In the drawings which show by way of illustration one embodiment of the invention:

Fig. 1 is a view in vertical section through a portion of a machine embodying the improvements with the nozzle closed and the end positioned for coating.

Fig. 2 is a similar view but showing the nozzle opened and the sealing material flowing therefrom.

In the application, Serial No. 251,092, filed by Frederick A. Prahl and Henry A. Fink, February 1, 1928, there is shown and described a machine for coating can ends wherein a nozzle is arranged beneath the can end to be coated and the sealing material forced by pressure to flow from the nozzle onto the surface to be coated. In this machine there is a valve located within the nozzle to control the flow of the sealing material from the nozzle. When the valve is moved to position for opening the nozzle a space is formed between the valve stem and the nozzle opening which must be filled with sealing material before the sealing material will flow from the nozzle.

The present invention has to do with a device associated with a nozzle of the above type which device is provided with a closed chamber in which air may be trapped by the sealing material. This device is connected to the nozzle adjacent the delivery opening of the nozzle. When the nozzle is closed the sealing material is forced into the chamber and com-

presses air therein. When the nozzle is opened the expanding of the air will cause the sealing material to flow from the chamber and thus provide an additional supply which will quickly fill the space between the end of the valve stem and the nozzle opening so that the sealing material will be quickly discharged to the full capacity of the opening in the nozzle.

In the drawings only a portion of the machine referred to is shown. It consists of a support 1 on which is mounted a lower chuck 2. Said chuck is carried by a spindle 3 which is free to rotate in the support 1. Cooperating with the chuck 2 is an upper chuck 4. In the drawings the can end to be coated is indicated at 5. Said can end has a channel portion 6 with the outer edge thereof curled as indicated at 7. This forms a channel which faces downwardly.

Attached to the support 1 is a bracket member 8. This bracket member 8 is provided with a passageway 9 therein. At the upper end of the bracket member is a nozzle 10 which is detachably secured to the member 8. This nozzle has a discharge opening 11. Located within the passageway 9 is a valve stem 12 of the needle type. The upper end of this valve stem is tapered to a point as indicated at 13. The inner surface of the nozzle is tapered to conform to the taper on the end of the valve stem and when this valve stem is raised it will snugly fit the inner wall of the nozzle and extend into the opening 11 so as to close the same.

Attached to the member 8 is a supply pipe 14. The sealing material is supplied through this pipe 14 to the passageway 9 in the member 8 as indicated in the broken lines in the drawing. The sealing material is supplied under pressure. When the valve stem is lowered and the discharge opening of the nozzle freed, then the sealing material will flow through said discharge opening and against the surface of the channel in the can end, thus supplying said channel with a coating of sealing material.

Attached to the member 8 adjacent the nozzle 10 is an elbow pipe 15. This pipe is threaded into the member 8. Threaded into

the elbow member 15 is a device 16 which is formed with a chamber 17 which is closed to the atmosphere. When the valve stem is closed the sealing material will be forced 5 into this device 16 and rise therein to the line A—A. Thus it is that air is trapped in the upper end of the chamber 17 and when the valve is closed this air will be compressed by the pressure exerted on the sealing material. 10 The valve is closed and the air is under compression, as shown in Fig. 1. When the valve is opened, as shown in Fig. 2, then there is a space formed between the end of the valve stem and the discharge opening in the nozzle 15 which must be first filled with sealing material before the sealing material can flow from the opening in the nozzle. This space is partly filled by the supply of sealing material from the pipe 14 and an additional supply of material will be quickly supplied to fill 20 said space from the chamber 17 due to the expanding of the air in the chamber. The pipe 15 connects with the passageway 9 very close to the nozzle so that there is a very quick 25 response when the valve is opened and the space filled with the sealing material so that as soon as it begins to flow from the nozzle it will flow in a stream of full capacity. The line B—B in Fig. 2 indicates the level of the 30 sealing material in the chamber 17 when the air has expanded to force a portion of the sealing material from the chamber into the passage leading to the nozzle.

The can end is rotated in the structure referred to above and if a very thin stream of sealing material is first supplied which increases to maximum capacity, there will be an uneven coating of the can end. It is very essential that the end shall be evenly coated 40 all the way around and the channel completely coated within the limits desired. This can best be accomplished when the nozzle, when it begins to discharge the sealing material, shall furnish a stream of sealing material 45 of maximum capacity. Furthermore when the stream of sealing material is of maximum capacity the number of revolutions given the can end to complete the coating thereof may be greatly reduced for the reason 50 that the coating will start at full capacity when it first strikes the channel in the can end, and, of course, it will immediately stop when the valve is closed. This enables the can end to be rotated to a sufficient extent 55 after the flow of the sealing material ceases so as to lay any trailing end within the desired coating limits. This avoids the soiling of the can end when moved laterally from the chuck by laying any trailing end onto 60 the parts of the end which should not be coated.

While the invention is shown and described in connection with a nozzle supplying the coating from beneath the can end, it will be 65 understood, of course, that the device is

equally applicable to coating nozzles arranged above the can ends or in any other relation to the can end. The essential feature resides in the capability of supplying a stream of sealing material of full capacity almost instantaneously when the valve is opened. 70

It is obvious that minor changes in the details of construction and the arrangement of the parts may be made without departing from the spirit of the invention as set forth in the appended claims. 75

Having fully described my invention what I claim as new and desire to secure by Letters Patent, is:—

1. A machine for coating can ends including a coating nozzle to which a sealing material is applied under pressure, a valve for closing said nozzle, means for rotatably supporting a can end relative to the nozzle, and a device adjacent the nozzle having a chamber closed to the atmosphere and connected to the nozzle in which air is trapped and compressed by the sealing material, the expansion of the air in said chamber operating to quickly supply sealing material from said chamber to the nozzle when the valve is opened. 80

2. A machine for coating can ends including means for rotatably supporting the can end with the channel thereof facing downwardly, a coating nozzle located beneath said can end for discharging sealing material delivered to the nozzle under pressure against the surface to be coated, a valve for closing the nozzle, and a device adjacent the nozzle having a chamber therein closed to the atmosphere and connected to the nozzle in which air is trapped and compressed by the sealing material, the expansion of the air operating to quickly supply sealing material from the chamber to the nozzle when the valve is opened. 90

3. A machine for coating can ends including a coating nozzle to which sealing material is applied under pressure, a valve stem located within the nozzle having a valve at the end thereof for closing the discharge opening of the nozzle, means for rotatably supporting a can end relative to the nozzle, and a device adjacent the nozzle having a chamber closed to the atmosphere and connected to the nozzle in which air is trapped and compressed by the sealing material, the expansion of the air operating to quickly supply sealing material from the chamber to the nozzle when the valve is opened. 100

4. A machine for coating can ends including a coating nozzle to which sealing material is applied under pressure, a valve stem located within the nozzle having a valve at the end thereof for closing the discharge opening of the nozzle, means for rotatably supporting a can end relative to the nozzle, an L-shaped pipe connected to the member supporting the nozzle and having a passage leading to the 110

passage through which the sealing material flows to the nozzle, and a device connected to said pipe having a chamber therein closed to the atmosphere and in which air is trapped and compressed by the sealing material.

5 In testimony whereof, I affix my signature.

GEORGE FRANCIS HARTMAN.
